(57) **CLAIM**

The ornamental design for RV screen door latch, as shown and described.

DESCRIPTION

FIG. 1 is a front top perspective view of a RV screen door latch showing our new design, with the bolt shown in extended position;

FIG. 2 is a front view of the RV screen door latch of FIG. 1.

FIG. 3 is a left side view of the RV screen door latch of FIG. 1.

FIG. 4 is a right side view of the RV screen door latch of FIG. 1.

FIG. 5 is a rear view of the RV screen door latch of FIG. 1.

FIG. 6 is a top view of the RV screen door latch of FIG. 1.

FIG. 7 is a bottom view of the RV screen door latch of FIG. 1.

FIG. 8 is a front top perspective view of a RV screen door latch, with the bolt shown in retracted position;

FIG. 9 is a front view of the RV screen door latch of FIG. 8.

FIG. 10 is a left side view of the RV screen door latch of FIG. 8.

FIG. 11 is a right side view of the RV screen door latch of FIG. 8.

FIG. 12 is a rear view of the RV screen door latch of FIG. 8.

FIG. 13 is a top view of the RV screen door latch of FIG. 8; and,

FIG. 14 is a bottom view of the RV screen door latch of FIG. 8.

The dashed lines indicate unclaimed portions and form no part of the claimed design.
